(57) **CLAIM**

The ornamental design for an outside mirror of car, as shown and described.

DESCRIPTION

FIG. 1 is a first perspective view of an outside mirror of car showing my new design;

FIG. 2 is a front elevation view thereof;

FIG. 3 is a rear elevation view thereof;

FIG. 4 is a first side elevation view thereof;

FIG. 5 is a second side elevation view thereof;

FIG. 6 is a top plan view thereof;

FIG. 7 is a bottom plan view thereof; and,

FIG. 8 is a second perspective view thereof.

The broken lines depict portions of the outside mirror in which the design is embodied that form no part of the claimed design.
